UNITED STATES PATENT OFFICE.

ANTON KURKA, OF PHILLIPS, WISCONSIN.

WRENCH.

1,402,505.

Specification of Letters Patent.

Patented Jan. 3, 1922.

Application filed March 8, 1921. Serial No. 450,576.

To all whom it may concern:

Be it known that I, ANTON KURKA, a citizen of Czecho-Slovakia, and resident of Phillips, in the county of Price and State of 5 Wisconsin, have invented certain new and useful Improvements in Wrenches; and I do hereby declare that the following is a full, clear, and exact description thereof.

This invention refers to a quick adjustable wrench, and it has for its object to provide a simple, economical and effective wrench of this general type, wherein the construction and arrangement is such that the wrench can be cheaply manufactured, 10 and at the same time is capable of the various instantaneous adjustments demanded, having means for exerting a positive locking bite upon the article, by a simple rotary movement of the handle.

20 With the above and other objects in view, the invention consists in certain peculiarities of construction and combination of parts, as are hereinafter set forth with reference to the accompanying drawing and 25 subsequently claimed.

The drawing illustrates a side elevation of a wrench embodying the features of my invention, with parts broken away and in section, to more clearly illustrate details of 30 construction.

Referring by character to the drawing, 1 represents a housing formed with a transversely disposed aperture 2 therein, and terminating at its upper end with a fixed jaw 35 member 3. The housing aperture is intersected by a longitudinally disposed bore 4, into which bore is loosely mounted the spindle 5, having attached to its upper end a worm 6, which worm is revolubly seated 40 within the housing aperture.

The lower end of the spindle has rigidly secured thereto, a handle of standard type 5', whereby the wrench is operated and the spindle is revolved under certain conditions.

45 The housing is also provided with an offset longitudinally disposed shell 7, which shell is adapted to receive the shank 8 of the sliding jaw 8'. The lower end of the jaw shank is provided with a slot 9, whereby 50 the shank is anchored, there being an anchor pin 10 for the shank, which extends transversely through the shell walls and shank slot 9. The front edge of the jaw shank is provided with a series of teeth 11, 55 which teeth are adapted to meshingly en-

gage the teeth of the worm 6 when the jaw is in its normal frictioning position.

The teeth are held in mesh by a leaf spring 12, which is secured to the rear wall of the shell 7, and is adapted to impinge 60 against the rear edge of the jaw shank.

From the foregoing description it will be seen, that when it is desired to approximately fit the wrench jaws to a nut or the like, the slidable jaw 8' is pulled backwardly, by hand, to the position indicated in dotted lines, which movement is opposed by the spring 12. This movement backwardly of the slidable jaw, is effected about an arc described from the center of the anchor pin 10, and due to the rocking movement it is obvious that the teeth 11 will be disengaged from the worm 6. Hence the operator can spread the jaws apart, or contract them, by sliding the shank 8 up or 70 down so as to bring the lower gripping face of the slidable jaw 8' to a position with relation to its companion jaw, whereby the nut can be gripped after the adjustment has been effected. 80

If it is desired to firmly bite the nut between the jaws, the operator simply twists the handle 5' slightly, whereby rotation of the worm is effected, which is in mesh with the teeth 11, and thus the sliding jaw will 85 be positively drawn snugly against the machine element to which the wrench is applied. Obviously the jaws will be locked, due to the worm gear connection of the parts, and the nut can readily be turned. To 90 loosen the grip of the nut, the operator may simply revolve the shank 5 in the proper direction.

While I have shown and described jaws having parallel faces for gripping the nut 95 or other machine element, obviously the device is capable of being used as a pipe wrench, in which the gripping faces of the jaws may be corrugated or said gripping jaw faces may be varied to suit other conditions to which the tool may be applied. 100

While I have shown and described one specific means for carrying out my invention, it is understood that I may vary the structural features within the scope of the 105 claim.

I claim:

A quick adjustable wrench comprising a transversely apertured housing terminating with a lower jaw and having an offset lon- 110

gitudinally disposed shank receiving shell, a slideable jaw having a shank provided with a slot in its lower end and a toothed front edge slideable in said shell, a revoluble handle spindle journaled in the housing and intersecting the aperture thereof, a worm revolvably mounted within the housing aperture, and secured to the end of the spindle, an anchor pin extending through the shell

shank slot, whereby said shank can be adjusted up or down, or back and forth, and a spring carried by the shell for pressing the toothed edge of the jaw shank into meshed engagement with the worm.

In testimony that I claim the foregoing I have hereunto set my hand at Phillips, in the county of Price and State of Wisconsin.

ANTON KURKA.
